RADIANT HEAT FUEL BURNER

Frederic O. Hess, Philadelphia, Pa., assignor to Selas Corporation of America, Philadelphia, Pa., a corporation of Pennsylvania

Application August 24, 1954, Serial No. 451,780

6 Claims. (Cl. 126—39)

This invention relates to a radiant heat fuel burner. More specifically, the invention concerns a burner of the type disclosed and claimed in the co-pending application of John Roger Williams, Serial No. 418,858, filed March 26, 1954.

Fuel burners in accordance with the Williams application have been found to be useful and efficient when used as burners for kitchen ranges. In making the burners and installing them in the kitchen ranges, it has been found that the sheet metal top panels of many kitchen ranges are not precisely flat. Moreover, it has been found that the top panels tend to warp to a limited extent as a result of the heat of the burner, and the extent of such warpage is increased with increased intensity of heat, which is conducted from the burner to the top panel of the range.

It is accordingly an object of this invention to provide an improved radiant heat fuel burner structure which overcomes the heating and warping problems just described. Still another object of this invention is to provide a kitchen range having a radiant heat gas burner which is suspended from the top panel of the range, and which is therefore free to move with the top panel if all or any part of the top panel should move. Still another object of this invention is to minimize the transfer of heat from the burner structure to the top panel of the range, thereby minimizing the warpage of the top panel and providing a cooler exposed range surface.

Still another object of this invention is to provide a connecting and sealing means associated with the top panel of a kitchen range and with the exposed cover plate of the radiant heat gas burner, which sealing means not only secures the respective parts together but also protects the internal parts of the gas burner against damage from spilled foods, fluids, etc.

Another object of this invention is to provide a radiant heat gas burner having an improved and simplified feed means for the gas and air. Other objects and advantages of this invention, including the simplicity and economy of the same, and the ease with which the invention may be applied to ranges and other heaters of various types, will further become apparent hereinafter and in the drawings, whereof:

Fig. 1 represents a vertical sectional view taken as indicated by the lines and arrows I—I which appear in Fig. 3, showing one specific form of the invention wherein a radiant heat gas burner is suspended from a top panel of a range in accordance with this invention;

Fig. 2 represents a view in side elevation of the upper portion of the apparatus shown in Fig. 1, certain parts being broken away and shown in section in order more particularly to illustrate important details;

2

Fig. 3 represents a plan view of the apparatus shown in Figs. 1 and 2;

Fig. 4 represents a sectional view taken as indicated by the lines and arrows IV—IV which appear in Fig. 3; and

Fig. 5 represents schematically a burner of this invention connected to an exhaust means.

Turning now to the specific embodiment of the invention selected for illustration in the drawings, the radiant heat fuel burner is substantially similar in many respects to the burner disclosed in the aforementioned copending Williams application. Although the burner will be described as a gas burner for the sake of convenience, it will be appreciated that other fuels may be substituted.

The number 20 designates a refractory ring above which is spaced a cover plate 21 of heat transmitting material such as special glass which is resistant to thermal shock but transparent to heat rays and preferably to visible light rays as well. The refractory ring 20 and cover plate 21 form an intervening combustion space 22 in which gas and air are burned. The number 23 designates an inspirator forming a partial premix of gas and air which flows to the combustion space through an annular space located between a vertical inner tube 24 and a concentric outer tube 25. Secondary air flows upwardly through the tube 24, mixing with the partial premix in the combustion space 22 and igniting in said combustion space forming hot combustion products. The combustion products flow radially outwardly across the surface of the refractory ring 20 and then flow downwardly through passages 28 extending through the refractory ring into an annular exhaust duct 26. Outlet pipe 27 is connected to the exhaust duct 26 and communicates with a sleeve 30 which is connected to a suction means such as a blower 19 or the like (which is shown in Fig. 5). Accordingly, suction is applied to the exhaust duct 26, which induces the flow of secondary air into the combustion space 22, and which exhausts the hot combustion products from the combustion space 22 and from duct 26. In this manner the surface of the refractory ring 22 is heated to incandescence, whereby generating intense radiant heat which is transmitted vertically through the heat transmitting cover plate 21.

In accordance with this invention a novel clamping and suspending means is provided for suspending the radiant heat gas burner from the top panel of the heating device. In the drawings, the number 31 designates the top panel of a heater such as a kitchen range for example. The panel 31 has a circular opening which is slightly larger than the diameter of the cover plate 21 and which accordingly accommodates the upper portion of the radiant heat burner. The top panel 31 has an arched ridge 32 which extends around the edge of the circular opening. The top panel 31 also carries a plurality of depending inwardly flanged members forming seats 33, and the upper portion of the exhaust duct 26 has wings 34 which are seated on top of the seats 33. A sealing ring 35 bridges over the arched ridge 32 to a shoulder 38 formed at the edge of the cover plate 21. Affixed to the bottom face of seal ring 35 is a depending clamp ring 36 which is substantially perpendicular to the top panel 31 and extends down into the space between the top panel 31 and the cover plate 21. The clamp ring 36 is slotted vertically at 37 (Fig. 2) and horizontally at 40 forming a clamping extension 41 which extends horizontally below the horizontal slot 40. The extension 41 engages the bottom surface of seat 33 while

the upper portion of clamping ring 36 engages the top face of wing 34. Accordingly it will be appreciated that the seal ring 35 and clamp ring 36 secure the cover plate 21, top panel 31, wings 34 and seats 33 in a fixed relative position, thereby firmly securing the radiant heat burner to the top panel 31.

It will be appreciated that the burner and top panel are readily assembled by placing the cover plate 21 on top of the exhaust duct 26, the spacing of the cover plate 21 being determined by a spacer ring 42 formed at the top of the exhaust duct 26. The wings 34 are then fitted on the seats 33, and the seal ring and clamp ring structure 35, 36 is applied downwardly, the vertical slot 37 being aligned vertically with the seat 33 and wing 34. The seal ring 35 is then displaced circumferentially, whereupon each clamping extension 41 engages the corresponding seat 33, clamping it to the burner wing 34 immediately above.

It will accordingly be appreciated that the radiant heat burner is suspended from the top of the range, and is free to rise and fall should the range top warp. Moreover, the burner fits snugly against the range top even though the latter may not be exactly level.

In accordance with this invention, not only is the disadvantageous effect of the burner heat substantially eliminated, but the extent of such heat is also greatly reduced. It will be observed that the inner surfaces of the exhaust duct 26 are insulated by means of a ceramic liner 44 which covers said inside surface. The liner 44 may comprise a separate casting having the same shape as the inside surfaces of the exhaust duct 26. On the other hand, other forms of insulating surfaces may be substituted, and the ceramic insulation may be applied in other ways, as will readily be apparent.

Turning to the fuel combustion portion of the apparatus, it will be observed that the inner tube 24 has an outwardly extending flange 43 having a plurality of vertically extending openings 45 which are arranged substantially perpendicular to the cover plate 21. It will be appreciated that the partial pre-mix consisting of gas and air flows vertically through the openings 45 into the combustion space 22. Although it has heretofore been believed necessary to introduce the partial pre-mix in a radial direction outwardly across the combustion space 22, it has now been discovered that excellent combustion characteristics are obtained in accordance with the new construction just described. The radial flow of secondary air from the tube 24 coacts with the vertical gas flow to form a flat, uniform flame which spreads out radially against the surface of the refractory disc 20. This is an excellent flame since it quickly and uniformly heats the refractory ring to incandescence.

It will be appreciated that the radiant heat gas burner preferably includes automatic pilot operated means for igniting the mixture of gas and air, as well as other apparatus, as illustrated in the aforementioned co-pending patent application of John Roger Williams. Such features are not shown in the drawings, inasmuch as they constitute no part of the present invention.

It will further be appreciated that either raw gas or partial pre-mix may be provided in the annular space between the tubes 24, 25. Such space or passage is referred to for convenience herein as a gas passage or space, although other fuels may be substituted, mixed with air or in the raw state.

Although this invention has been described by reference to one specific embodiment thereof, it will be apparent to those skilled in the art that various changes other than those referred to above may be made in the form of the device, that equivalent elements may be substituted for those illustrated in the drawings, and that certain features of the invention may be used to advantage independently of the use of other features, all within the spirit of the invention as defined in the appended claims.

Having thus described my invention, I claim:

1. Domestic cooking apparatus comprising means forming a substantially flat substantially horizontal top panel having an opening therein, said top panel having a plurality of downwardly extending seat members spaced around said opening, and a radiant heat fuel burner including as a part thereof an annular exhaust duct smaller in diameter than said opening and having substantially horizontal extensions arranged for seating engagement upon said seat members, and means for securing said duct to said seat members whereby said radiant heat fuel burner is suspended from said top panel, said last mentioned means bridging the space between said opening and said annular exhaust duct.

2. Domestic cooking apparatus comprising means forming a substantially flat substantially horizontal top plate, said top plate having a substantially circular aperture therein, said top plate including an annular ridged portion spaced from and concentric with said aperture, and said top plate also having depending seat portions spaced below the edge of said aperture, a fuel burner including a supporting structure having outwardly extending wings arranged for seating engagement on said seat portions, whereby said burner is supported from said top, said burner having a heat transparent cover plate located in approximately the plane of said aperture, and means to fasten said burner and cover plate in said aperture including a seal ring bridging from radially outward of said annular ridged portion to radially inward of the edge of said cover plate.

3. Domestic cooking apparatus as defined in claim 2, wherein said seal ring includes a depending clamping portion having opposed clamping members arranged respectively to engage the upper surfaces of said wings and the lower surfaces of said seats.

4. In a domestic cooking apparatus including a substantially horizontal panel having an opening therein and a radiant heat gas burner having a support on which a substantially flat heat-transmitting cover plate is mounted, connecting means for suspending the burner from the top panel comprising means forming a seat fixed to said panel, means forming a wing fixed to said support, said wing being seated on top of said seat, a substantially rigid seal member arranged in the general plane of said top panel and said cover plate bridging from said panel to said plate, and a clamping means fixed to the bottom of said seal member extending downwardly at the edge of said opening between said cover plate and said top panel, said clamping means engaging both said seat and said wing thereby securing the seat, wing, top panel and over plate in fixed relative positions.

5. Domestic cooking apparatus comprising means forming a substantially flat and horizontally disposed top panel having an aperture therein, seating members extending inwardly from the edge of said aperture, a gas burner including a body and a cover therefor, said body being provided with outwardly projecting supporting wings and being of a size to be received in said aperture with said wings resting on said seats, a clamping ring extending from a position radially outward of said aperture over said top to a point radially inward of the edge of said cover to bridge the space between the two, and means forming part of said ring engaging said wings and seats to lock wings and seats together and thereby hold said cover on said burner and said burner in position on said top.

6. Domestic cooking apparatus comprising means forming a substantially flat and horizontally disposed top panel having an aperture therein, a gas burner adapted to be received in said aperture and supported by said panel, said burner including a body having provisions to supply fuel and air thereto and a rim extending radially therefrom, a cover plate for said body of a size to rest on said rim, cooperating means on said panel and body to support said burner in said aperture with said cover plate substantially flush with said panel, a ring of a size

to extend radially beyond the edge of said aperture and radially inward of the edge of said cover plate to bridge the space between the two, and means carried by said ring engaging said cooperating means to lock said burner in position in said aperture.
